UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINDLE AND BEARING.

SPECIFICATION forming part of Letters Patent No. 609,758, dated August 23, 1898.

Application filed November 30, 1897. Serial No. 660,211. (No model.)

To all whom it may concern:

Be it known that I, GEORGE O. DRAPER, of Hopedale, county of Worcester, State of Massachusetts, have invented an Improvement in Spindles and Bearings, of which the following description, in connection with the accompanying drawings, is a specification, like letters on the drawings representing like parts.

This invention relates to spinning-spindles; and it has for its object the production of novel means for supporting the bolster in the bolster-case in such manner that the bolster may be easily adjusted vertically to effect the proper fit between the pintle of the spindle and the bolster.

Figure 1 is a vertical sectional view of a spindle-bearing embodying my invention, and Fig. 2 is a perspective detail of the bolster-support detached.

The spindle S, having a tapering pintle, the bolster-case B, having a threaded shank B' to receive a nut B², by which the case is retained in position on the rail C, the sleeve-whirl W, secured to the spindle, and the bolster D, as to its general features, may be and are of usual or well-known construction.

Referring to Fig. 1, the upper end of the bolster is surrounded and frictionally engaged by a bolster-support, shown as a collar F, slotted or split at f, Figs. 1 and 2, which

support rests on the upper end of the bolster-case. The bolster is thus suspended from the support within the bolster-case, and while the frictional grip of the support on the bolster is sufficient to retain the latter in adjusted position the bolster may be moved longitudinally relatively to the support to effect vertical adjustment of the bolster, the spindle-pintle being extended into the bolster, and then both are inserted in the bolster-case until the pintle strikes the step.

A spindle step or end bearing D^X is shown in Fig. 1 on the bottom of the closed end of the bolster-case.

Having fully described my invention, what I claim, and desire to secure by Letters Patent, is—

The combination with a bolster-case, of a bolster, and an expansible annular support for and to frictionally engage the bolster, said support being carried by and at the upper end of the case.

In testimony whereof I have signed my name to this specification in the presence of two subscribing witnesses.

GEORGE O. DRAPER.
